UNITED STATES PATENT OFFICE.

CHARLES H. CROWELL, OF BROOKLYN, NEW YORK.

CONTAINER.

Application filed December 24, 1919. Serial No. 347,201.

To all whom it may concern:

Be it known that I, CHARLES H. CROWELL, a citizen of the United States, and resident of the borough of Brooklyn, county of 5 Kings, city and State of New York, have made a certain new and useful Invention Relating to Containers, of which the following is a specification taken in connection with the accompanying drawing.

10 This invention relates especially to containers for shipping purposes in which the parts are so constructed, fastened and sealed as to be practically non-pilferable. The container which may be made of corrugated paper board, fibre board or other suitable material may comprise a container body formed of one or more pieces or sections of such material, and for relatively small containers a single strip or piece of 15 corrugated paper having transversely scored portions may be folded up into the desired form. The side seams between the adjacent ends of such container body material, which may if desired have cooperating 20 bevelled edges, may be secured by a connector or retainer strip of adhesive or gummed cloth or paper tape which may be secured to the outside of the container body and have inturned ends folded around 25 the edge portions so as to engage, and if desired overlap, each other on the inside of the container body. It is also desirable to provide the container body member, or the top or bottom cover cooperating therewith, 30 with an outer projecting edge flange so as to form a stepped or rabbeted edge on the container body, for instance, within which the top or bottom cover or both, may be received and cemented in such way that the 35 inner concealed portions of these cooperating members are glued or cemented together to still further minimize pilfering or facilitate detection thereof. The creased or scored seam portions of the body may be 40 reinforced by suitable tape inside or outside of the container body and the other edge seams thereof may be provided with retainer strips of gummed tape or the like which preferably have inturned ends for a 45 similar purpose. When the top and bottom of the container have been secured in place the edge seams around the same may be closed by suitable sealing strips of 50 gummed cloth or paper tape which preferably have flexible or pliable seam portions to facilitate attachment.

In the accompanying drawing showing in a somewhat diagrammatic way an illustrative embodiment of this invention,

Fig. 1 is a perspective view of a container 60 partly in section.

Fig. 2 is a partial transverse section thereof taken substantially along the line 2-2 of Fig. 1; and

Fig. 3 is a diagrammatic perspective 65 view showing a way in which the stepped edge of the container body may be formed.

In the illustrative embodiment of the invention which is shown in Fig. 1 of the drawing the container body which may as 70 indicated be formed of corrugated paper board may be creased or scored at the desired points to form the corner portions or seams, such as 13 as shown in Fig. 2, and these portions may be reenforced by the 75 fold reinforcing tape, such as 11, which may advantageously be forced into the fold or crease for this purpose. When these creases extend transversely across the corrugated paper definite sizing of the parts 80 is promoted so that they are readily interchangeable as well as given increased strength under these conditions. In the case of relatively small containers the container body may often be formed of a single 85 strip or piece of corrugated paper board, fibre board or the like from which the sides 1, 2, 3 and 4 may be formed, although for larger boxes or containers two or more pieces of material may be used to form the 90 body, the edge seams between the pieces of body material being preferably secured by body connector or retainer strips, such as 15, which may be pasted or otherwise adhesively secured on the outside of the 95 body seam and may have portions 18 extending around the edges thereof so as to form inturned ends 16, 17 secured on the inside of the container body to give greater strength and much greater protection 100 against pilfering. If desired also other retainer strips, such as 35, may in any case be used or arranged on the other edge seams of the container body so as to give similar protection against pilfering.

105 In many cases it is advantageous to form the container body with a stepped or rabbeted edge portion or with a projecting edge flange such as 5 which may extend around one or both ends of the container body to accommodate the top or bottom 110 which cooperate therewith. For this pur-

pose the corrugated paper board or other material may advantageously be slit and then formed into this stepped or rabbeted configuration, one arrangement for effecting this being diagrammatically shown in Fig. 3. A slitting device such as the rotary slitting saw 23 may first engage the edge 24 of the sheet of corrugated paper board or the like and then after the upper portions have been slit or cut through in this way along the line 25 a rotary knife or planer device such as 22, may readily and rapidly remove the upper portions of this edge so as to leave a stepped edge on the material comprising an inner edge 7 and an inner face 5 which is a projecting edge flange and extends part or all the way around the top and bottom of the container body. It is of course understood that this container body is preferably given such a projecting edge flange configuration before the connector or retainer strips of gummed cloth or paper tape, such as 15, 35, are applied thereto, so that these strips can be closely pasted or cemented to the edge flange to take up a minimum of space at these points.

The top and bottom of the box, such as 10, 14, may be formed of corrugated paper board or other material of such size as to fit into the container body preferably within the edge flanges thereof and these members may advantageously be glued or cemented in place as by the glue 27 indicated in Fig. 1 as extending within this stepped or flanged edge portion of the container body so as to cement the concealed inside portions of these cooperating elements which of course makes it more difficult to separate the parts without such tearing or other injury as makes the detection of pilfering easy and inevitable. The inturned ends of the retainer or connector strips also contribute to this result since they cannot of course be applied after the container cover or top is in place in such way as to properly secure their inturned ends in the original position. When the top and bottom are secured in place the seams around these members may be closed by the use of sealing strips of cloth or paper tape, such as 6 and 9 which may be pasted over these seams to thus give added protection against dirt and moisture and to give additional strength and security to the package.

This invention has been described in connection with a number of illustrative embodiments, forms, portions, parts, materials, arrangements and methods of manufacture and use, to the details of which disclosure the invention is not of course to be limited, since what is claimed as new and what is desired to be secured by Letters Patent is set forth in the appended claims.

1. The non-pilferable shipping container comprising a container body formed of a

single piece of corrugated paper board material having each seam where the ends of the body material are joined secured by a retainer strip of tape adhesively secured to the outside of the body material and having inturned ends which are brought around the edges of the body material and secured to the inside of the container body, the edges of said container body having a stepped form to provide a projecting outer flange and a cooperating top and bottom formed of corrugated paper board cooperating with the stepped edge portions of said container body and cemented within the projecting flanges thereof. 70 75 80

2. The non-pilferable shipping container comprising a container body formed of paper board material having each seam where the ends of the body material are joined secured by a retainer strip of tape adhesively secured to the outside of the body material and having inturned ends which are brought around the edges of the body material and secured to the inside of the container body, the edges of said container body having a stepped form to provide a projecting outer flange and a top and bottom cooperating with the stepped edge portions of said container body and cemented within the projecting flanges thereof. 90 95

3. The non-pilferable shipping container comprising a container body member formed of a single piece of corrugated paper board material having reinforced scored portions at each edge seam and having the seam where the ends of the body material are joined secured by a retainer strip of tape adhesively secured to the outside of the body material and having inturned ends which are brought around the edges of the body material and secured to the inside of the container body and a cooperating top cover member formed of corrugated paper board and cooperating with said container body member, the edges of one of said members having a stepped form to provide a projecting outer flange having an inner concealed portion cemented to the cooperating member. 100 105 110

4. The non-pilferable shipping container comprising a container body member formed of a single piece of paper board material and a cooperating cover member formed of paper board and cooperating with said container body member, the edges of one of said members having a stepped form to provide a projecting outer flange and having an inner concealed portion cemented to the cooperating member. 115 120

5. The non-pilferable shipping container comprising a container body member formed of paper board material, and a cooperating cover member formed of paper board and cooperating with said container body member, the edges of one of said members having a projecting outer flange and having an in- 125 130

ner concealed portion secured to the cooperating member.

6. The shipping container comprising a container body formed of a single piece of corrugated paper board material having reinforced scored portions at each edge seam, the edges of said container body comprising portions having a stepped form to provide a projecting outer flange and a cooperating top cover formed of paper board cooperating with the stepped edge portions of said container body and cemented within the pro-

jecting flanges thereof and sealing strips closing the seams around said cover.

7. The shipping container comprising a 15 container body formed of paper board material, the edges of said container body comprising portions having a stepped form to provide a projecting outer flange and a cooperating cover cooperating with the stepped 20 edge portions of said container body and cemented within the projecting flanges thereof.

CHARLES H. CROWELL.
